UNITED STATES PATENT OFFICE.

GEORGE W. MILLER AND EDWIN S. GEORGE, OF DETROIT, MICHIGAN.

DESIGN FOR A FENCE-PANEL.

47,006.

Specification for Design.

Patented Feb. 23, 1915.

Application filed November 23, 1914. Serial No. 873,651. Term of patent 14 years.

To all whom it may concern:

Be it known that we, GEORGE W. MILLER and EDWIN S. GEORGE, a subject of the King of Great Britain and Ireland and a citizen of the United States of America, respectively, residing at Detroit, in the county of Wayne and State of Michigan, have invented a certain new, original, and ornamental Design for Fence-Panels, of which the following is a specification, reference being had therein to the accompanying drawings, forming part thereof, in which the figure represents a plan view of a fence panel, showing our new design.

We claim:

The ornamental design for a fence panel, substantially as shown.

GEORGE W. MILLER.
EDW. S. GEORGE.

Witnesses:

JAMES P. BARRY,
HENRI E. BOWMAN.
